(57) **CLAIM**

The ornamental design for an adjustable guard for hair clippers, as shown and described.

DESCRIPTION

FIG. 1 is an isometric view of an adjustable guard for hair clippers showing our new design;

FIG. 2 is another isometric view of the adjustable guard for hair clippers of FIG. 1;

FIG. 3 is a front elevational view of the adjustable guard for hair clippers of FIG. 1;

FIG. 4 is a right side elevational view of the adjustable guard for hair clippers of FIG. 1;

FIG. 5 is a rear elevational view of the adjustable guard for hair clippers of FIG. 1;

FIG. 6 is a left side elevational view of the adjustable guard for hair clippers of FIG. 1;

FIG. 7 is a top plan view of the adjustable guard for hair clippers of FIG. 1; and,

FIG. 8 is a bottom plan view of the adjustable guard for hair clippers of FIG. 1.

The broken lines represent portions of the adjustable guard for hair clippers that form no part of the claimed design.
